DUAL PRESSURE GAS BURNER

John H. Flynn, New Rochelle, N. Y.

Application March 5, 1947, Serial No. 732,495

2 Claims. (Cl. 158—104)

1

The present invention relates to improvements in dual-pressure gas-burners, i. e., gas burners which have two types of gas outlets respectively supplied with combustible gas at different pressures to thus provide a main flame and a supporting or sustaining flame to maintain the ignition of the combustible gas providing the said main flame.

One of the major uses for dual-pressure gas-burners is in connection with the soldering of cans and other containers, especially as a feature of automatic machines wherein reliable and effective operation is imperative.

One of the main objects of the present invention is to provide a superior dual-pressure gas-burner which is reliable and effective in operation.

Another object of the present invention is to provide a gas-burner of the character referred to which may be readily assembled and disassembled in a minimum period of time to thus minimize the "down-time" of equipment with which the gas burner is used.

A further object of the present invention is to provide a superior dual-pressure gas-burner the vital parts of which will remain clean and serviceable over long periods of use.

Still another object of the present invention is to provide a superior dual-pressure gas-burner having a construction and arrangement of parts whereby, when required, cleaning may be largely effected by the mere act of disassembling the parts.

With the above and other objects in view, as will appear to those skilled in the art from the present disclosure, this invention includes all features set forth in the appended claims.

In the accompanying drawings, in which certain modes of carrying out the present invention are shown for illustrative purposes:

Fig. 1 is a broken view mainly in plan and partly in horizontal section of one form of dual-pressure gas-burner constructed in accordance with the present invention;

Fig. 2 is a view thereof in front elevation;

Fig. 3 is a transverse sectional view taken on the line 3—3 of Fig. 1, but on a larger scale;

Fig. 4 is a broken detail sectional view taken on the line 4—4 of Fig. 3;

Fig. 5 is a perspective view of one of the jet-studs detached;

Fig. 6 is a view mainly in plan and partly in horizontal section of another form of dual-pressure gas-burner constructed in accordance with the present invention;

2

Fig. 7 is a sectional view taken on the line 7—7 of Fig. 6;

Fig. 8 is a perspective view of a modified form of jet-stud suitable for carrying out the present invention;

Fig. 9 is a view in side elevation of still another form of jet-stud; and

Fig. 10 is a transverse sectional view taken on the line 10—10 of Fig. 9.

The gas-burner of Figs. 1 to 5 inclusive

In the figures referred to, there is illustrated a linear type of dual-pressure gas-burner which includes a distributor-body generally designated by the reference character 10 and which may be conveniently formed of cast metal. The said distributor-body includes a front wall 11, a parallel rear wall 12, a longitudinal partition 13, end walls 14 and 15, a top wall 16 and a bottom wall 17.

The partition 13 above referred to extends from end to end of the distributor-body 10 as is indicated in Fig. 1, and serves to divide the interior of the said distributor-body into a high-pressure distributing-channel 18 and a low-pressure distributing-channel 19 extending in parallelism with each other from the end wall 14 to the end wall 15 of the distributor-body.

Extending vertically through the bottom wall 17 of the distributor-body 10 about midway the length thereof and communicating directly only with the high-pressure distributing-channel 18, is an inlet-port 20. Threaded or otherwise connected to the inlet-port 20 is a supply-pipe 21 leading from a suitable source of a combustible gas such, for instance, as a source of a mixture of hydrocarbon gas and air.

In the particular instance shown and as will be observed by reference to Fig. 3 in particular, the partition 13 within the distributor-body 10 comprises three reaches, namely, a lower upwardly-and-rearwardly-inclined reach 22, a substantially-horizontal reach 23 and a substantially-vertical reach 24. The substantially-vertical reach 24 is formed with a port 25 providing communication between the high-pressure distributing-channel 18 and the low-pressure distributing-channel 19.

At its rear, the port 25 is shaped to provide a conical valve-seat 26 adapted to be cooperated with by the conical inner end of a screw-valve 27 extending rearwardly through the rear wall 12 of the distributor-body 10. The external threads of the screw-valve 27 are engaged with internal threads formed within a bushing 28

which, in turn, is threaded or otherwise removably connected to the rear wall 12. Preferably and as shown, there is also provided a jam-nut 29 threaded onto the outer portion of the screw-valve 27 and adapted to seat against the rear face of the bushing 28 to firmly hold the screw-valve in any given position of adjustment.

At spaced intervals throughout its length, the inclined-reach 22 of the partition 13 is provided with a plurality of threaded passages 30 extending between the high-pressure distributing-channel 18 and the companion low-pressure distributing-channel 19, as is indicated in Fig. 3. The said passages 30 are inclined upwardly and forwardly toward the front wall 11 which latter is formed with a similarly spaced series of passages 31. The passages 31 just referred to are respectively arranged in axial alignment with threaded passages 30.

Each of the passages 31 above referred to together with its companion threaded passage 30, is adapted to receive one of a plurality of similar jet-studs 32 each of which is generally designated by the reference character 32 and each of which is preferably formed of stainless steel or other suitable corrosion-resistant material.

Each jet-stud 32 comprises a body 33 and a sleeve 34, which latter is materially shorter than the said body. The respective opposite ends of the body 33 are both reduced in diameter to provide an outwardly-facing annular stop-shoulder 35 and an inwardly-facing stop-shoulder 36. Mounted with a force fit upon the reduced outer portion of the body 33 is the sleeve 34 before referred to. The said sleeve has its inner edge seated against the outwardly-facing stop-shoulder 35 but has an external diameter exceeding the external diameter of the intermediate portion of the body 33 and fitting the adjacent passage 31 in the front wall 11 with a snug turning fit.

The sleeve 34 above referred to is formed in its periphery with an annular series of substantially-longitudinal groove-like low-velocity gas-passages 37 providing communication between the low-pressure distributing-channel 19 and the outer end of the jet-stud 32 of which the said gas-passages form a feature.

The outer end of the body 33 of each jet-stud 32 is formed with a kerf 38 by means of which a given jet-stud may be turned. The reduced inner end of each body 33 adjacent the inwardly-facing stop-shoulder 36 is externally threaded to form a stem 39 which is adapted to thread into the adjacent one of the threaded passages 30 in the partition 13 in such manner that the said stop-shoulder 36 firmly seats against the forward face of the said partition, all as is indicated in Fig. 3.

Extending axially through the body 33 of each jet-stud 32 is a high-velocity gas-passage 40 terminating at its inner end at the end face of the stem 39 and terminating at its outer end in the bottom of the kerf 38. The said gas-passage 40 provides communication between the high-pressure distributing-channel 18 in the distributor-body 10 and the outer end of the given jet-stud 32.

The upper front corner of the distributor-body 10 is preferably beveled as at 41 to provide a seat for a strip-like shield 42 which may be conveniently produced of cast iron or the like. The rear portion of the shield 42 extends over the forward portion of the top wall 16 proper

and may be secured thereto by a suitable number of screws 43.

The lower edge of the shield 42 is formed with a plurality of downwardly-opening notches 44 respectively registering with the passages 31 in the distributor-body 10 and each having a width substantially corresponding to the diameter of the said passages 31. Preferably and as shown, the curved upper wall 45 of each of the said notches 44 is inclined and shaped to substantially correspond to the registering portion of the adjacent passage 31.

Operation of the gas-burner of Figs. 1 to 5 inclusive

Assuming that a combustible gas is being supplied under relatively-high pressure to the high-pressure distributing-channel 18, such gas will flow with high velocity outwardly through the high-velocity gas-passage 40 in each of the jet-studs 32 for projection outwardly beyond the outer end of a given stud to provide a jet-flame indicated by the broken lines 46 in Fig. 3. The degree of projection of the high-velocity gas emerging from each of the gas-passages 40 will depend upon the pressure maintained within the high-pressure distributing-channel 18 and may, for instance, be from about three-quarters of an inch to about one and one-half inches.

The screw-valve 27 may be so adjusted that its conical inner end is spaced sufficiently from the valve-seat 26 to maintain a relatively-low pressure in the low-pressure distributing-channel 19. The low-pressure combustible gas will pass outwardly through the low-velocity gas-passages 37 in each of the jet-studs 32 and will provide around each jet-flame 46 a substantially-annular supporting-flame indicated by the broken lines 47 in Fig. 3. The volume of the supporting-flame may be regulated by moving the screw-valve 27 with respect to the valve-seat 26.

Different combustible-gas mixtures will have different rates of flame-propagation and since such combustible-gas mixtures will emerge from the respective high-velocity gas-passages 40 at a rate of speed which will be usually in excess of the flame-propagation speed referred to, the auxiliary or supporting-flame 47 is provided in order to maintain the ignition of the associated jet-flame 46. Thus, under ordinary conditions, the higher the velocity of the combustible-gas mixtures emerging from the high-velocity gas-passages 40, the higher should be the supporting-flame 47 in order to maintain the adjacent jet-flame continuously ignited. As before pointed out, the volume of the various supporting-flames 47 may be concurrently regulated by the manipulation of the screw-valve 27.

In instances where a dual-pressure gas-burner of the character above described is used in connection with the soldering of cans or the like, it is customary to brush off excess solder by means of revolving brushes, and such excess solder is very apt to be thrown partly lengthwise of the distributor-body and thus impinge upon the outer ends of the jet-studs 32 unless such occurrence is guarded against in a manner which will not interfere with either the jet-flames 46 or the supporting-flames 47.

The strip-like shield 42 has proven effective in avoiding the impingement of solder or other foreign matter against the outer ends of the gas-passages 37 and 40. Such foreign matter is most apt to collect against one side of the

notches 44 in the shield 42 and may be readily removed by first removing the shield 42 from the distributor-body 10 and brushing out the said notches.

Periodically, but at relatively-long intervals, it will be desirable to remove the various jet-studs 32 from the distributor-body 10, and this may be accomplished by simply inserting a tool in the kerf 33 of a given jet-stud 32 and unthreading the stem 39 thereof from the complementary threaded passage 30 in the partition 13. The turning movement of a given jet-stud 32 as just referred to, will cause the edges of the groove-like low-velocity gas-passages 37 to act more or less as a reamer and hence dislodge accumulated foreign matter from the adjacent wall of the passage 31.

The gas burner of Figs. 6 and 7

In Fig. 6 is shown a distributor-body generally designated by the reference character 48, similar in basic characteristics to the distributor-body 10 but being of ring-like form rather than of linear form.

The distributor-body 48 includes a front wall 49, a rear wall 50, a partition 51, a top wall 52 and a bottom wall 53. Like the distributor-body 10 before described, the distributor-body 48 may be conveniently formed of cast iron or other suitable metal.

The distributor-body 48 is provided in its front or inner wall 49 with a spaced-apart series of passages 54 similar to the passages 31 before described and each of which is in axial alignment with a threaded passage 55 formed in the partition 51 and corresponding to the threaded passages 30 before referred to. The partition 51 is formed with a port 56 corresponding in function to the port 25 and like the same, having a conical valve-seat which, in this instance, is designated by the reference character 57.

The valve-seat 57 above referred to is adapted to cooperate with the inner end of a screw-valve identical with the screw-valve previously described and therefore bearing the same reference character 27. The said screw-valve is mounted in the rear or outer wall 50 and has associated with it the same features as have been before described and which, therefore, bear similar reference characters.

The bottom wall 53 of the distributor-body 48 is provided with an inlet-port 58 through which a combustible-gas mixture may be admitted into the high-pressure distributing-channel 59 in the distributor-body 48. The said high-pressure distributing-channel extends completely around the interior of the distributor-body 48 and is partitioned off from a similarly-shaped low-pressure distributing-channel 60 by the aforesaid partition 51.

Installed in each of the passages 54 and in their respective aligned threaded passages 55, is one of the aforesaid jet-studs 32.

The dual-pressure gas-burner illustrated in Figs. 6 and 7 and above described may function in the same manner as has been described in connection with the showing of Figs. 1 to 5 inclusive.

The jet-stud of Fig. 8

In Fig. 8 is illustrated a modified form of jet-stud suitable for use in lieu of the jet-studs 32 before described and designated generally by the reference character 61.

The jet-stud 61, in the instance shown, is 75

formed of one piece of metal and is formed at its inner end with a threaded stem 62 and at its outer end with a kerf 63. Adjacent its outer end over a portion substantially corresponding in location to the sleeve 34 previously referred to, the jet-stud 61 is formed with a polygonal-portion 64, the apices of which are sized to snugly fit into a suitable passage such as 31 or 54 and to cooperate with the wall of such a passage to provide six (more or less) low-velocity gas-passages each of which would have its inner boundary provided by the faces 65 of the said polygonal-portion 64. In effect, the flat faces 65 just referred to provide gas-passages inasmuch as they come radially closer to the longitudinal axis of the jet-stud than do the apices 66 of the said polygonal-portion 64.

Extending longitudinally through the jet-stud 61 is a high-velocity gas-passage 67 similar to the high-velocity gas-passage 40 in the jet-studs 32 before described.

The jet-stud of Figs. 9 and 10

In Figs. 9 and 10 is illustrated a further alternative form of jet-stud which is generally designated by the reference character 68 and which is adapted to be utilized in lieu of either the jet-studs 32 or the jet-studs 61 before described.

The jet-stud 68 is formed at its inner end with a stem 69 and at its outer end with a kerf 70 respectively functioning in the same manner as the stems 39 and 62 and the kerfs 38 and 63 before described.

The forward portion of the jet-stud 68 corresponding to the location of the sleeve 34 of the jet-stud 32 is reduced in diameter to form a forwardly-facing stop-shoulder 71 and to have wrapped therearound a corrugated or fluted piece of sheet metal 72. The apices of the corrugations of the sheet-metal piece 72 are sized so as to fit passages such as 31 and 54 and to extend higher than the immediately adjacent rear portion of the jet-stud to permit gas to flow interiorly of the flutes or corrugations, as well as through the exterior groove-like spaces between the same. In this manner, an annular series of low-velocity gas-passages are provided.

Extending longitudinally through the jet-stud 68 is a high-velocity gas-passage 73 serving in the same manner as the previously described high-velocity gas-passages 40 and 67.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A dual-pressure gas burner, comprising a casing having an internal partition dividing it into a high-pressure chamber and a low-pressure chamber, a cylindrical outlet in said casing and communicating with said low-pressure chamber, and a tapped through-passage in said partition in axial alignment with said outlet; and a jet-plug having a longitudinal core provided with a longitudinal high-pressure-gas through-passage and a threaded inner end received in said tapped passage for removably mounting said core in installed position in which the same extends with clearance through said outlet, and circumferentially spaced longitudinal ribs projecting out-

wardly from said core and being, in the installed position of the latter, in engagement with a length of said outlet other than an outer end-length thereof to define in said outlet a plurality of low-pressure gas passages, the outer end of 5 said core being provided with means for releasable interlock with a tool with which to turn the plug for its installation in and removal from the casing, and said threaded core end being longer than said end-length of said outlet so that said 10 ribs will be in brushing engagement with said entire end-length on screwing the plug from and into the casing.

2. A dual-pressure gas burner as set forth in 15 claim 1, in which said ribs are provided with relatively sharp outer edges which are in scraping engagement with said outlet on screwing the plug from and into the casing.

JOHN H. FLYNN
